UNITED STATES PATENT OFFICE.

WILLIAM J. P. MOORE, OF NEW YORK, N. Y.

DESIGN FOR A RADIATOR FOR AUTOMOBILES AND OTHER VEHICLES.

50,110.

Specification for Design.

Patented Dec. 26, 1916.

Application filed September 30, 1916. Serial No. 123,190. Term of patent 7 years.

To all whom it may concern:

Be it known that I, WILLIAM J. P. MOORE, a citizen of the United States, and resident of New York, in the county of New York and State of New York, have invented a new, original, and ornamental Design for Radiators for Automobiles and other Vehicles, of which the following is a specification, reference being had therein to the accompanying drawing.

Figure 1 is a front elevation of a radiator for automobiles and other vehicles showing my new design. Fig. 2 is an edge view of the same.

I claim:

The ornamental design for a radiator for automobiles and other vehicles, as shown.

In testimony whereof I hereunto affix my signature.

WILLIAM J. P. MOORE.
